US00D768153S

(12) United States Design
Fornaciari et al.

(10) Patent No.: US D768,153 S
(45) Date of Patent: ** Oct. 4, 2016

- (54) **DISPLAY SCREEN OR PORTION THEREOF WITH ANIMATED GRAPHICAL USER INTERFACE**

(71) Applicant: **salesforce.com, inc.**, San Francisco, CA (US)

(72) Inventors: **Matthew Gregory Fornaciari**, San Francisco, CA (US); **Ken Wakamatsu**, San Francisco, CA (US); **Arthur Ping-Tak Che**, San Francisco, CA (US); **Sahil Bhutani**, Emeryville, CA (US)

(73) Assignee: **salesforce.com, inc.**, San Francisco, CA (US)

(**) Term: **15 Years**

(21) Appl. No.: **29/537,289**

(22) Filed: **Aug. 24, 2015**

(51) LOC (10) Cl. **14-04**

(52) U.S. Cl. USPC **D14/485**

CLAIM

The ornamental design for a display screen or portion thereof with animated graphical user interface, as shown and described.

DESCRIPTION

FIG. 1 is a front view of a display screen or portion thereof with animated graphical user interface showing a first image of our new design; and,

FIG. 2 is second image thereof.
The outermost broken lines in the Figures show a display screen or portion thereof, and form no part of the claimed design. The other broken lines in the Figures show portions of the animated graphical user interface that form no part of the claimed design.

1 Claim, 2 Drawing Sheets
